UNITED STATES PATENT OFFICE.

JOSEPH ROY, OF CLEVELAND, OHIO, ASSIGNOR TO AMERICAN STOVE COMPANY, OF ST. LOUIS, MISSOURI, A CORPORATION OF NEW JERSEY.

GAS-RANGE FRAME.

1,333,507.

Specification of Letters Patent.

Patented Mar. 9, 1920.

Application filed August 7, 1919. Serial No. 315,941.

To all whom it may concern:

Be it known that I, JOSEPH ROY, a citizen of the United States, residing at Cleveland, in the county of Cuyahoga and State of Ohio, have invented certain new and useful Improvements in Gas-Range Frames, of which the following is a specification, reference being had therein to the accompanying drawing.

10 This invention relates to improvements in gas range frames.

This invention pertains to a frame for a gas-range, which has at its base a cabinet, above and at one end of the cabinet upper 15 and lower ovens, and an open burner frame in a horizontal plane between the two ovens constituting a warming space or oven below the open burner frame.

The primary object of this invention is to 20 provide a frame for a gas range of the above described type, which is relatively cheap to manufacture, easily assembled, and when assembled is rigid and effective for the purpose.

25 The object of the present invention further pertains to certain details of construction whereby the foregoing primary object is accomplished, which details will be pointed out hereinafter.

30 In the accompanying drawings—

Figure 1 is a front elevation of a gas range which embodies my improved frame construction.

Fig. 2 is a perspective view of the frame 35 shown in skeleton arrangement.

Fig. 3 is a transverse vertical sectional view on the line 3—3 of Fig. 2, looking in the direction indicated by arrow.

Fig. 4 is a detail view of the door guide- 40 ways.

My improved frame comprises front and rear band-irons 1, and end band irons 2. These band irons 1 and 2 are secured to the peripheral flange 3, of a bottom or base pan 45 4, the latter being preferably in an inverted position. The band-irons are secured to the flange 3, preferably by suitable screw bolts 5, though rivets could be used. An upright L-angle iron 6 has its lower end 7 bolted 50 through the lapping ends of the band-irons 1 and 2, and through the flange 3 of the base pan 4.

A division band-iron 8 extends horizontal 55 throughout the width of the range and is located in a horizontal plane with the top of

the base cabinet 9. One end 10 of the band-iron 8 is bolted to the standard 6, intermediate its ends and the other end 11 of this band iron 8 is bolted to the long arm 12 of the frame 13. The long arm 12 of the frame 13 is integral with the top 14 of the frame and the frame is provided with an integral short inner arm 15. This frame 13 is made of an L-angle iron notched out at *a* to permit it to be bent in rectangular shape, as shown. The lower end 16 of the arm 15 of the frame 13 is in the horizontal plane of the upper edge of the band-iron 8. A horizontal band iron 17 has one end 18 bolted to the long arm 12, and its opposite end 19 bolted to the short 70 arm 15. This construction forms a front frame for the upper and lower ovens 20 and 21.

An open burner frame 22 is made of L-shaped angle-iron, which is notched as at *b*, to permit it to be bent in angular shape, as shown.

The outer front corner 23 of this frame is bolted to the upper end of the standard 6, and its outer rear corner is bolted to the upper end of a rear band-iron standard 25, the lower end of the band-iron standard 25 being bolted to the adjacent ends of the base band-irons 1 and 2, and to the flange 3, of the base pan 4, as at 26.

The open L-angle iron frame 22 has its ends *c* drawn tightly together and fastened. As here shown, these ends are held by a lapping plate 27, which is riveted as shown to the horizontal portion of the frame 22. This 90 plate 27 forms the double function of uniting the ends *c* of the frame 22, and acting as one burner hanger for the burners (not shown) that are supported within the frame 22. A second burner hanger 28 is riveted 95 to the rear portion of the frame 22, as shown.

Suitable burner manifold hangers 29 are bolted to the front end of the frame 22 and project outward to receive and embrace a 100 manifold (not shown) for the open frame burners (not shown).

The front end of the base cabinet 9 is provided with parallel horizontally slidable doors 30 and 31. One feature of my present 105 invention pertains to the specific construction of slide-ways for these doors, which are bolted to and form part of the frame, and serve not only as guide-ways for the doors, but as stiffening members for the base of 110

the range. These guide-ways are formed from a strip of sheet metal and bent in W-form, as shown at 32. The front portion of the sheet thus formed of the lower guide-way A has a widened flange 33, which in the case of the bottom guide extends downward and is clamped between the flange 3 of the base pan 4, and the front lower angle-iron 1. The upper guide-way B has the W-form 32', and an upwardly extending widened flange 32', which extends along the inner face of the band iron 8 and is bolted thereto. The inner free edges of the W-form of both guide-ways A and B are stiffened by the 15 double and lateral bends 34.

From this it will be observed that the widened flange of the lower guide A extends downward, while the widened flange of the upper guide B extends upward. This 20 W-form 32 and 32' provides two horizontal parallel guide-ways for the doors 30 and 31, whereby they are slideable past each other to permit access to all parts of the base cabinet 9 and at the same time enables the front of 25 the cabinet to be entirely closed.

The range is provided with a sheet metal back 35, which extends upward back of the open burner frame 22, as shown at 36, and the top of the cabinet 9 is formed by a suitable inverted pan-shaped division wall 37. The side walls (not shown) of the range are formed of sheet metal and attached to the range frame in any suitable manner.

Referring to the open burner frame 22, attention is directed to the fact that in shaping this up V-shaped notches are cut from the horizontal web of a straight bar, and the vertical web of the straight bar is bent at the apex of the notches. By reason of this 40 fact after being bent, it has a tendency to spring open at the notched portion and it is essential to hold it tightly closed. This is accomplished by drawing the ends together and holding them by the riveted 45 burner hanger 27.

Having thus described my invention, what I claim and desire to secure by Letters Patent is:—

1. A gas range frame, comprising an inverted pan-shaped bottom, horizontal band irons secured to the flange of the bottom, a frame 13 having long and short arms, the lower end of its long arm connected to one corner of the base, a standard 6 projecting 50 upward from the other front corner of the base, a rectangular open burner frame, having its outer front corner supported by the standard 6, a horizontal bar 8 connecting the standard 6, and the long arm of the frame 13, the upper edge of the bar arranged under the short arm 15 of the frame 13, and a rear standard for the rectangular open burner frame, substantially as described.

2. A gas range frame comprising an in-

verted pan-shaped bottom, band irons secured to the outer side of the depending flange of the pan, a frame 13 having long and short arms, the lower end of its outer long arm connected to one front corner of the base, the upper end of the frame 13 extending inward and having a downwardly extending relatively short arm 15, a standard 6 projecting upward from the other front corner of the base, a rectangular open 75 burner frame having its outer front corner attached to the upper end of the standard 6, and its inner front corner about midway the short arm of the frame 13, a member 8 having its ends connected with the standard 6, and a long arm of the frame 13 with its upper edge under the lower end of the short arm of the frame 13, and a horizontal member 17 with its ends connected to the vertical arms of the frame 13 in approximately the horizontal plane of the rectangular open burner frame, for the purpose described.

3. A gas range frame of the type described, having a cabinet at its lower end, 90 parallel door guide-ways at the front edge of the cabinet, the guide-ways formed from a sheet bent into W form, and attached at the top and bottom of the front edge of the cabinet.

4. A gas range frame comprising a cabinet having sliding doors, double horizontally arranged door guide-ways, the guide ways formed of a sheet bent into W form, one side of the W having an elongated flange 100 for the purpose of securing the guide-ways in position, substantially as described.

5. A gas range frame comprising a cabinet provided with sliding doors, upper and lower guide-ways for the doors, the upper 105 guide-way formed of a sheet of metal bent in W form and having an upwardly extending securing flange, and a lower guide-way formed from a sheet bent in W-form having at its front edge a downwardly extending 110 securing flange, whereby the guideways are secured in position in the frame.

6. A double door guide-way for gas ranges made of an elongated sheet bent in W-form, the sheet at one side of the W provided with an extending flange, for the purpose described.

7. A double door guide-way for gas ranges, made of a sheet bent in W-form, the sheet having an extending securing flange 120 at one side and a lateral extending stiffening flange at the other side of the W-form.

8. A gas range frame, comprising a cabinet at its bottom with an open front, a double horizontally extending guide-way at the top and bottom of said open front, each guide-way formed of an elongated sheet bent in W-form in cross-section with the stems of the W composed of two thicknesses of the sheet tightly engaging each other to form 125 130

stiffened stems, one of the outer stems having its outer wall extended and fastened to the horizontal edge of the said open front.

9. A gas range frame comprising a cabinet at its bottom having an open front, of double horizontally arranged door guide-ways at its upper and lower edges, each guide-way formed of an elongated sheet bent in W-form in cross section, each stem

of the W composed of two thicknesses of the sheet tightly engaging, one wall of the outer stem projecting vertically to form a securing flange and the outer wall of the other outer stem extending laterally for the purpose described.

In testimony whereof I hereunto affix my signature.

JOSEPH ROY.
